UNITED STATES PATENT OFFICE.

BOYD EDMISTON AND HENRY T. KINNEY, OF PUNXSUTAWNEY, PENNSYLVANIA.

DESIGN FOR A BOTTLE.

Application filed March 27, 1928. Serial No. 26,036. Term of patent 14 years.

To all whom it may concern:

Be it known that we, BOYD EDMISTON and HENRY T. KINNEY, citizens of the United States of America, residing at Punxsutawney, in the county of Jefferson and State of Pennsylvania, have invented a new, original, and ornamental Design for a Bottle, of which the following is a specification, reference being had to the accompanying drawing, which forms a part thereof.

In the drawing:—

We claim:

The ornamental design for a bottle, as shown.

BOYD EDMISTON.
HENRY T. KINNEY.
